DIRECTIONAL CONTROL DEVICE

Eugene C. Ecker, Albuquerque, N. Mex.

Application April 24, 1934, Serial No. 722,180

2 Claims. (Cl. 114—172)

The invention relates to a directional control device and more especially to a foot depressed and turned directional control.

The primary object of the invention is the provision of a device of this character, wherein under the action of the foot of a person, the control of a moving vehicle for the directional course thereof may be effected, as for example, the rudder of a boat may be regulated from the foot of an operator or occupant of the boat by pressure of the foot and the turning of the same for directing the course of such boat and the adjustment of the rudder maintained in a determined position, or the said rudder freely adjusted for the quick altering of the directional course of the boat.

Another object of the invention is the provision of a device of this character, wherein the directional control of a moving object may be had through applied foot pressure combined with a rotative movement of such pressure and thus eliminating the necessity of the use of the hands of a person for actuating such control, the device being applicable for the directional movement of aircraft, landcraft, watercraft, elevators, mechanical shovels, swinging crane arms or other mechanisms and appliances without aid of the hands of a person or inconvenience to the latter or excessive labor.

A further object of the invention is the provision of a device of this character which is extremely simple in its construction, thoroughly reliable and effective in its purposes, readily and easily actuated, assuring safe and easy control, strong, durable, and inexpensive to manufacture and install.

With these and other objects in view the invention consists in the features of construction, combination and arrangement of parts as will be hereinafter more fully described in detail, illustrated in the accompanying drawings, which disclose one form of embodiment of the invention, and pointed out in the claims hereunto appended.

In the accompanying drawings:

Figure 1 is a fragmentary vertical longitudinal sectional view through a boat showing an outboard motor unit and rudder, with the device constructed in accordance with the invention applied.

Figure 2 is an enlarged fragmentary vertical longitudinal sectional view through the device.

Figure 3 is a view similar to Figure 2.

Figure 4 is a sectional view on the line 4—4 of Figure 2.

Figure 5 is a fragmentary elevation.

Figure 6 is a top plan view partly broken away.

Figure 7 is a sectional view on the line 7—7 of Figure 4.

Figure 8 is a sectional view on the line 8—8 of Figure 4.

Similar reference characters indicate corresponding parts throughout the several views in the drawings.

Referring to the drawings in detail, A designates generally a portion of a boat, this being illustrated merely to show one mode of application of the device constituting the present invention, and B is an outboard motor constituting the driving unit for the propeller C, the latter being carried by the rudder 10 for said boat. The rudder 10 is turned through the medium of a gear 11 meshing with a companion pinion 12 rotated from a shaft 13 inboard of said boat.

The device, in the application to the boat A, comprises a suitable housing 14 which is arranged within the boat body at the desired locality. In one end portion of the housing 14 is a driven pulley 15 having the universal coupling 16 with the shaft 13.

Suitably fitted in the base of the housing 14 at the other end thereof is a stud axle 17 upon which is loosely journaled a control pulley 18 about which is trained the belt 19 which is also trained about the pulley 15, so that these will operate in unison with each other. Upon the stud axle 17 is loosely fitted a hub 20 for a turning disk or table 21, the same being exteriorly of and above the housing 14. The hub carries a spring tensioned latch 22 to engage with an annular channel or groove 23 exteriorly formed in the stud axle 17 so that in this manner the said hub is releasably engaged with the axle. The hub is not only free for rotation upon the axle 17 but it also has a limited vertical sliding movement corresponding to the depth of the groove or channel 23 in said axle.

The lower side of the hub is provided with a clutch face 24 for engaging a clutch face 25 at the upper side of the pulley 18, while the inner side of the top of the housing 14 is provided with a clutch face 26, this cooperating with a clutch face 27 on said pulley 18. Therefore, it will be seen that the pulley 18 may be latched with the top of the housing 14 and also latched with the hub 20 of the turntable 21. When these parts are in latched relation, and particularly when the pulley 18 is clutched with the housing, the said pulley 18 is prevented from turning and likewise the table 21.

Surrounding the stud axle 17 below the pulley

18 is a coiled compression spring 28, the same resting upon the bottom of the housing 14 at its lower end and against a crown piece 29 at its upper end, this piece being countersunk in 5 the under face of the pulley 18 and made secure therein, the spring 28 being adapted to urge the pulley 18 upwardly for the latching of the same with the housing, so that the pulley will be locked against turning movement. The crown piece 29 10 is formed with an outturned annular flange 30 offset from the under face of the pulley 18 and constituting a seat for a pedal 31, the latter having the center yoke 32 encircling the said crown piece 29, and this pedal is loosely pivoted, at 33, 15 within the housing at one side of the stud axle 17, while at the other side of the latter the pedal is extended through a Z slot 34 formed in the side of the housing 14, so that the outside end of the pedal can be foot manipulated. On the 20 passing of the pedal in the slot 34 from the highest end thereof, which is the normal position, into the lower end, the spring 28 will be compressed and thus lowering the pulley 18 on the stud axle 17 for unclutching this pulley from 25 the housing 14 and in this position the turntable 21 can be turned to impart rotation to said pulley 18, the rotary movement of the pulley being transmitted by the belt 19 to the pulley 15 and its motion transferred to the rudder 10 for the 30 directional control of travel of the boat A, as will be apparent. When the pedal is returned to normal position in the slot 34, that is to say, at the highest end of said slot, the pulley 18 will be clutched with the top of the housing 14 and 35 thus locked against turning movement. It will be apparent that on the raising and lowering of the pulley 18 upon the stud axle 17 the hub 20 will be constantly in clutched engagement with said pulley.

40 The turntable 21 is designed for foot applied power so that a person can step upon the said table 21 and by downward pressure unlatch or

unclutch the pulley 18 from the top of the housing 14 and by a rotary motion of the foot upon the table 21 while depressed, the rudder 10 can be regulated for the directional course of travel of the boat A. The instant that the pressure of the foot is released from the table 21, the spring 28 acts upon the pulley 18 to clutch it with the top of the housing 14 and thereby latch the rudder in its adjusted position, unless the pedal 31 is moved from normalcy to unclutch the pulley 18 from the top of said housing, and in this position the rudder 10 will not be latched but can be freely turned by foot pressure upon the table 21 and slight turning of the foot under this application. 80

It should be obvious that the device is susceptible of many applications for directional control of an object and, therefore, it is to be understood that the invention is not limited to the expressed application in the drawings and the foregoing description except as come within the scope of the claims hereunto appended. 85

90 What is claimed is:

1. In a device of the character described, a driven pulley, a power pulley, connections between the pulleys, means for clutching the power pulley to hold the same stationary, foot operated means for releasing the power pulley from clutched position and for driving the same, and a pedal for moving the power pulley from clutched 100 position. 105

2. In a device of the character described, a driven pulley, a power pulley, connections between the pulleys, means for clutching the power pulley to hold the same stationary, foot operated 110 means for releasing the power pulley from clutched position and for driving the same, a pedal for moving the power pulley from clutched position, and means for detachably clutching the foot operated means with the power pulley. 115
